CONDITIONING APPARATUS

William Neil Bray, Leicester, England, assignor to
 United Shoe Machinery Corporation, Borough
 of Flemington, N. J., a corporation of New
 Jersey

Application September 27, 1937, Serial No. 165,813
 In Great Britain November 12, 1936

13 Claims. (Cl. 91—46)

This invention relates to conditioning apparatus and is herein illustrated and described as embodied in a device for subjecting articles such as shoe stiffeners to the action of a conditioning medium for temporarily softening the stiffeners and rendering them adhesive preparatory to incorporating them in shoes.

It is the usual practice to stiffen the toe ends of shoes by inserting a stiffening member known as a box toe between the upper and the lining, the stiffener having first been conditioned by heat or by a suitable softening medium. However, in the case of certain types of shoes such as sandals, and particularly stitchdown or "Veldtschoen" sandals, in which the margin of the upper is turned outwardly and is secured upon the upper surface of the sole, no lining is employed. Instead of using the ordinary box toe to stiffen the toe portions of such sandals, a stiffening agent may be applied in liquid form. I have found it preferable in such work, however, to use a stiffener of solid sheet material such as Celluloid of, for example, about $\frac{1}{1000}$ of an inch in thickness and having formed over its entire area perforations of about $\frac{1}{20}$ of an inch or thereabouts in diameter, the centers of which are spaced about $\frac{1}{16}$ of an inch apart. Box toe pieces of the required dimensions may be cut from such material and dipped in a conditioning liquid, for example acetone, to soften them and also to render them adhesive.

It is an object of the present invention to provide an apparatus suitable for conditioning shoe stiffeners and particularly for conditioning stiffeners of the character above described. For a proper understanding of the conditions which must be met by such a machine it may be noted that a conditioning liquid such as acetone is both highly volatile and inflammable and must therefore be prevented from escaping into the atmosphere. Furthermore, for reasons which will later be pointed out, the extent to which the work piece should be softened is critical and involves accurate timing of the duration of immersion. In addition to meeting these requirements the machine should also be simple in construction and easy to operate.

The illustrated apparatus, which was constructed in view of the above-mentioned considerations, comprises a work holder movable by the operator between work-treating and loading or unloading positions through an opening formed in a receptacle for a volatile conditioning medium, which opening is normally closed by a yieldable member adapted to be opened by the work holder

in moving out of the receptacle and to close automatically to prevent the escape of vapor when the work holder moves into work-treating position within the receptacle. The work holder illustrated herein, in accordance with a further feature of the invention, is provided with a plate for closing the above-mentioned opening when the work holder is in loading or unloading position partially outside the receptacle.

These and other features of the invention will now be described as embodied in an illustrated machine and pointed out in the appended claims, reference being had to the accompanying drawing, in which

Fig. 1 is a view in side elevation and partly in section of the apparatus above referred to;

Fig. 2 is a front view, also partly in section, of the same apparatus; and

Fig. 3 is a perspective view of a work-holding grid of the apparatus.

Referring now to the drawing, the dipping apparatus comprises a casing 10 having an opening 12 in its front wall. A cover 14 is provided for the opening 12. The cover 14 opens outwardly, being hinged upon a pintle 18 carried by the casing 10 adjacent to the lower edge of the cover. The base of the casing is closed by a removable trough 20 held by pivoted bolts and wing nuts 21 and connected to a barometric feed device, comprising a reservoir 22 which has an opening projecting downwardly within a tray 24. A pipe 26 connects the trough 20 with the tray 24, and thus maintains a constant level of the liquid in the trough. At one side of the casing 10 the trough 20 is extended laterally to form a well 28 in which a brush 30, provided with a lid 32 to close the top of the well, is housed. Carried at the lower end of a rod 34, which is conveniently of square cross section and which extends through an aperture in a sliding plate 36 which closes the top of the casing, is a work holder in the form of a framework 38 of wire (Fig. 3) composed of two grids 40, 42, one above the other, connected together by a strip 44 which closes the back and the sides of the space between the grids. Carried by the grids is a plate 46 which, as shown in Fig. 1, acts to close the opening 12 in the casing when moved against the front wall thereof. The plate 46 has an opening through which the grids 40 and 42 extend forwardly and rearwardly.

The grids 40 and 42 have each a gap in their mid-portions to facilitate the placing between and removal from the space between the grids of work pieces by the operator, a corresponding

notch being formed in the cover 14 (Fig. 2) for the same purpose. The rod 34 is pivoted at its upper portion which extends outside of the casing 10 to the front end of a lever 48. The upper end portion of the rod 34 is formed as a handle. The lever 48 is pivoted midway of its length to a standard 50 upon which the casing 10 is fixed. The rear end of the lever 48 is connected to a hydraulic check device including a cylinder 52 and piston 54. A tension spring 56 tends to hold the front end of the lever 48, the shaft 34 and the work holder 38 raised. The shaft 34 is provided with an offset weight 58 which tends to swing the work holder 38 outwardly through the opening 12 in the wall of the casing in position for a blank to be removed from or placed between the grids. The movement of the work holder, however, is controlled by a cam plate 60 fixed inside the casing 10 with 20 which contacts a roll 62 carried on the shaft 34. The cam plate 60 is shaped to prevent the work holder from being swung forwardly while the bar 34 is in lowered position for dipping work pieces in the liquid in the trough 20. After the bar 34 has been raised by the tilting of the lever 48 under the tension of the spring 56 the cam plate 60 then permits the work holder to swing forwardly, but it prevents lowering of the work holder until the work holder has been swung 30 back again to a position over the trough 20.

As has been indicated, the tension spring 56 tends to maintain the rod 34 and work holder 38 raised and when in this position the work holder, under the influence of the counterweight 58, pushes the hinged cover 14 open, as shown in Fig. 1, the plate 46 then contacting with the inside face of the front wall and maintaining the interior of the casing closed against evaporation of the softening liquid. The forward movement of 40 the work holder is limited by an adjustable stop screw 80 threaded through the casing 10 and engageable with the rod 34. The slide 36 maintains the top of the casing closed despite movement of the rod 34.

45 The operation of the above described conditioning apparatus to soften articles such as shoe stiffeners of sheet Celluloid or of like material will now be explained. The apparatus normally comes to rest with the work holder 38 in its raised position as shown in Fig. 1 and projecting through the opening 12 in the front wall of the casing 10. A fresh dry stiffener is placed by hand between the grids 40 and 42 of the work holder, a softened stiffener being first removed if the apparatus 50 has previously been in operation. The work holder 38 is next withdrawn into the casing by pulling upon the handle at the upper end of the rod 34 and the rod is then depressed, against the pull of the spring 56, moving the grids and stiffener down into the liquid in the trough 20. During this movement liquid in the cylinder 52 flows freely through a one-way valve 64 in the piston 54 from the upper part of the cylinder into the part below the piston.

60 Directly the work holder has been fully depressed the rod 34 is released by the operator and the hydraulic check controls the speed of descent of the piston 54 and of rising of the work holder, an adjustable valve 66 controlling the return flow of liquid through a by-pass 68 connecting the spaces within the cylinder above and below the piston. An intermediate port 70 connecting the by-pass 68 with the cylinder allows free transfer of liquid during the last portion of rise of the work holder and thus enables the work holder to

move up quickly after the stiffener carried by it has been lifted clear of the conditioning liquid in the trough 20. As the rod 34 and work holder 38 reach their highest positions the weight 58 causes the work holder 38 to push the cover 14 open and present a softened stiffener conveniently for removal.

The timing of dipping of the stiffeners has an important bearing upon their subsequent affixation to the inside surfaces of the shoe uppers, it being most desirable to have the stiffeners softened only so far as to allow of their being handled, and without being jellified to such an extent as to stick to the fingers of the operator, to lose their outlines, or to break up when being taken from the apparatus and subsequently handled. A stiffener thus softened is transferred promptly by hand to and laid in proper position upon the inside, usually flesh, surface of an upper (assumed to be of leather) and lightly pressed thereon. More softening fluid is now brushed over the stiffener by means of the brush above mentioned. The already softened condition of the stiffener and the fact of its being perforated enable it quickly to absorb more liquid. Upon thus taking up sufficient of the extra solvent that has been brushed upon it the stiffener promptly fully jellifies and adheres firmly to the upper, becoming entangled to a large extent in the fibres which are always present to a greater or less degree on the flesh or inside surfaces of leather uppers, and becoming quickly and firmly keyed to the upper by the jellification of the material at its margins as well as at the perforations.

The exposed surface of a stiffener thus jellified upon an upper will normally become non-adherent again in a very few seconds, thus allowing the upper with the still limp stiffener to be handled or put away in contact with others promptly without detriment. When the upper is to be conformed to a last the celluloid layer, if it has become hard, can again be softened by a brief brushing on of solvent and any liability of its sticking to the last may be guarded against by greasing the necessary part of the last with petroleum jelly or the like.

The timing of dipping by the apparatus described may easily be varied to suit any particular grade of Celluloid by setting the adjustable valve 66. A dipping period of ten seconds more or less is ordinarily desirable, as it allows of a softened stiffener being placed upon an upper and treated for full jellification while a succeeding stiffener is being softened in the apparatus.

Having thus described my invention, what I claim as new and desire to secure by Letters Patent of the United States is:

1. A conditioning apparatus comprising a trough for a conditioning liquid, a work holder, a lever carrying said work holder, a fulcrum for up and down tilting movement of said lever to enable articles on said work holder to be dipped into and to be removed from conditioning liquid in said trough, a pivotal connection between said work holder and said lever arranged for swinging movement of said work holder between a normal position offset from said trough for loading and unloading said work holder and a position above the conditioning liquid in said trough, and a handle on said work holder arranged to enable the operator after loading the work holder with articles to be conditioned to swing the work holder from normal position to a position over said trough and then to lower the loaded work holder into the conditioning liquid in the trough.

2. A conditioning apparatus comprising a receptacle for a conditioning medium, a work holder movable between a position for loading and unloading from without said receptacle and a work-treating position inside of said receptacle, said receptacle having an opening through which said work holder is movable, and a yieldable closure for said opening constructed and arranged to be opened by said work holder in moving toward loading and unloading position and to close automatically when the work holder moves into work-treating position.

3. Apparatus according to claim 2 provided with a plate on said work holder constructed and arranged to close said opening as the work holder moves into said loading and unloading position.

4. A conditioning apparatus comprising a trough for a volatile conditioning liquid, a casing for preventing the escape into the atmosphere of vapor from said liquid, said casing having a front wall in which is formed an opening, a work holder, and supporting mechanism for said work holder constructed and arranged to enable said work holder to be moved through said opening between a position for loading and unloading from without said receptacle and a work-treating position wherein articles loaded on the holder are immersed in conditioning liquid in said trough.

5. Apparatus according to claim 4 provided with an automatic closure for said opening constructed and arranged to yield open when engaged by said work holder in moving toward loading and unloading position.

6. A conditioning apparatus comprising a trough for a volatile conditioning liquid, a casing for preventing the escape into the atmosphere of vapor from said liquid, said casing having a front wall in which is formed an opening, a work holder, a lever carrying said work holder, a fulcrum for up and down tilting movement of said lever to enable articles on said work holder to be dipped into and to be removed from conditioning liquid in said trough, a pivotal connection between said work holder and said lever arranged for swinging movement of said work holder through said opening between a position for loading and unloading from without said casing and a position above the conditioning liquid in the trough, and means for moving said work holder between loading and unloading position and dipping position.

7. Apparatus according to claim 6 provided with a guide constructed and arranged to prevent substantial tilting movement of said lever toward dipping position except when the work holder is over the trough and to prevent the work holder

from being swung forwardly while in dipping position.

8. Apparatus according to claim 6 provided with a guide constructed and arranged to prevent substantial tilting movement of said lever toward dipping position except when the work holder is over the trough and to prevent the work holder from being swung forwardly while in dipping position, and yieldable means urging the work holder from dipping position toward loading and unloading position.

9. A conditioning apparatus comprising a trough for a volatile conditioning liquid, a casing for preventing the escape into the atmosphere of vapor from said liquid, said casing having a front wall and a top wall, each of said walls having an opening, a work holder, a lever outside of said casing, an arm extending upwardly through said opening in said top wall, a pivotal connection between said arm and said lever arranged for swinging movement of the work holder through said opening in said front wall between a position for loading and unloading from without said receptacle and a position above the conditioning liquid in the trough, and a fulcrum for up and down tilting movement of said lever to enable articles on said work holder to be dipped into and to be removed from conditioning liquid in said trough, said arm being constructed and arranged to serve as a handle whereby the work holder may be moved from loading and unloading position to dipping position.

10. Apparatus according to claim 9 provided with yieldable means for automatically returning the work holder from dipping position to loading and unloading position.

11. Apparatus according to claim 9 provided with yieldable means for automatically returning the work holder from dipping position to loading and unloading position, and with a one-way checking device for retarding the initial portion of such return movement to insure sufficient exposure to the conditioning liquid.

12. Apparatus according to claim 9 provided with a cover for the opening in the top wall of the casing, said cover having an opening through which the arm of the work holder is freely movable and being slideable on the casing forwardly and rearwardly with the swinging of the arm to maintain the opening in the top wall of the casing effectively closed for all positions of the arm.

13. Apparatus according to claim 9 provided with means for guiding the work holder between loading and unloading position and dipping position.

WILLIAM NEIL BRAY.
